CLAIM

The ornamental design for a tire supported tool tray, as shown and described.

DESCRIPTION

FIG. 1 is a front elevational view of the tire supported tool tray of the present invention, the rear being a mirror image thereof;

FIG. 2 is a left side elevational view of the tire supported tool tray of FIG. 1;

FIG. 3 is a right side elevational view of the tire supported tool tray of FIG. 1;

FIG. 4 is a top plan view of the tire supported tool tray of FIG. 1;

FIG. 5 is a bottom plan view of the tire supported tool tray of FIG. 1; and,

FIG. 6 is a top, front, right side perspective view of the tire supported tool tray of FIG. 1.
